(57) CLAIM

The ornamental design for a flip-top with a touch screen, as shown and described.

DESCRIPTION

FIG. 1 shows a front elevation perspective view of flip-top with a touch screen.

FIG. 2 shows a top elevation view of a flip-top with a touch screen.

FIG. 3 shows a right elevation view of a flip-top with a touch screen.

FIG. 4 shows a bottom view of a flip-top with a touch screen; and,

FIG. 5 shows a rear view of a flip-top with a touch screen. The broken line portion of the figure drawings is included to show unclaimed subject matter only and forms no part of the claimed design.

1 Claim, 5 Drawing Sheets
